UNITED STATES PATENT OFFICE.

STEPHEN GREEN, OF LEBANON, MISSOURI, ASSIGNOR TO BARNA T. STOWELL, OF SAME PLACE.

IMPROVEMENT IN HOES.

Specification forming part of Letters Patent No. **158,373**, dated January 5, 1875; application filed November 30, 1874.

To all whom it may concern:

Be it known that I, STEPHEN GREEN, of Lebanon, county of Laclede and State of Missouri, have invented certain Improvements in Hoes.

The following description, taken in connection with the accompanying plate of drawings, hereinafter referred to, forms a full and exact specification, wherein are set forth the nature and principles of the invention, by which the same may be distinguished from others of a similar class, together with such parts thereof as are claimed as new and are desired to be secured by Letters Patent of the United States.

My invention relates to that class of agricultural implements called hoes; and the nature thereof consists in a certain novel combination of the parts of the same, as hereinafter shown and described.

In the accompanying plate of drawings, in which corresponding parts are designated by the same letters—

Figure 1 is a perspective view of the hoe. Fig. 2 is a side view of the same.

b designates the widest cutting-edge; *c*, the narrow cutting-edge. The sides of the lower blade *B* are slightly inclined from the perpendicular. The sides of the upper blade *C* are inclined at about the same angle. The upper and lower blades are connected by a central section, *D*, the sides of which are inclined from the perpendicular at an angle of nearly

forty-five degrees. The plane of the upper blade *C* is inclined at an angle of about thirty degrees from the plane of the lower blade.

A hoe of this construction presents a series of flat sides and straight edges, which may be ground upon a grindstone of any size.

The shank *H* of the hoe consists of the part *h*¹, which is perpendicular to the plane of the lower blade, and the part *h*², which, by means of the curvilinear section *h*³, may have any required angle with the part *h*¹. The part *h*¹ is united to the center of the central section *D* by passing the end *M* through an aperture cut through the thickest part of the blade, and riveting it thereto. The said part *h*¹ is provided with a shoulder, *N*, which fits against the inner side of the hoe, and serves to hold it firmly in place.

I claim and desire to secure by Letters Patent—

The hoe herein described, consisting of an angular blade, as shown, and a goose-neck tang attached at right angles to said blade by a collar and rivet, as specified.

In testimony that I claim the foregoing I have hereunto set my hand this 12th day of September, 1874.

STEPHEN GREEN.
